CARL A. PORATH, OF KOKOMO, INDIANA.

WIRE-COILING MECHANISM.

1,260,799.

Specification of Letters Patent. Patented Mar. 26, 1918.

Application filed October 19, 1917. Serial No. 197,476.

To all whom it may concern:

Be it known that I, CARL A. PORATH, a citizen of the United States, and a resident of Kokomo, county of Howard, and State of Indiana, have invented a certain new and useful Wire-Coiling Mechanism; and I do hereby declare that the following is a full, clear, and exact description thereof, reference being had to the accompanying drawings, in which like letters refer to like parts.

This invention relates to a wire coiling mechanism. One of the features of the invention is the provision of a head and mechanism therein for coiling a wire in spiral formation. Another feature of the invention is the provision of means for giving a positive drive to the head, thus forming the pitch of the spiral exactly uniform throughout the length of the wire.

Another feature of the invention is the provision of an adjustable part in the coiling mechanism whereby the pitch of the spirals may be varied. An additional feature of the invention is the provision of an adjustable non-rotating roller for engagement with the wire while passing through the coiling head, so that when a portion of the face of the roller becomes worn the roller may be loosened and turned until an unworn section thereof is brought into the path of the wire, when the roller is again locked against rotation. This feature of the invention permits the roller to be used until entirely worn out.

A further feature of the invention is the provision of a positive drive for the means employed for feeding the wire through the coiling head, which driving means co-operates with the positive driving means for the coiling head.

The full nature of the invention will be understood from the accompanying drawings and the following description and claims.

Figure 1 is a top plan view of the wire coiling machine. Fig. 2 is a side elevation of the upper portion of the coiling mechanism. Fig. 3 is a sectional view as seen on line 3—3, Fig. 1. Fig. 4 is a central longitudinal sectional view through the coiling head and parts coöperating therewith, the position of the coiling head being at right angles to the positions shown in Figs. 1 and 2. Fig. 5 is a sectional view as seen on line 5—5, Fig. 4. Fig. 6 is a face view of a roller employed in connection with the coiling mechanism. Fig. 7 is an edge elevation thereof. Fig. 8 is an elevation of one of the stays produced from the coiled wire.

Referring to the drawings in which similar reference numerals designate corresponding parts throughout the several views, 1 indicates a frame of any preferred construction in which is mounted a driving shaft 2, 60 said shaft being driven in any preferred manner. Fixed to the shaft 2 is a bevel gear 3 which meshes with a similar gear 4, said latter gear being attached to a second shaft 5, which is mounted in suitable bearings 6 on the frame 1.

Mounted upon the second shaft 5 is a sprocket gear 7 around which passes a sprocket chain 8, said chain also passing around a sprocket 9 carried by a tubular shaft 10.

The tubular shaft 10 is mounted in bearings 11 which bearings are preferably secured to the exterior face of the frame 1. The inner end of the tubular shaft 10 is 80 provided with a reduced neck portion 12 which is exteriorly threaded and enters the threaded end 13 of the coiling head 14, said head having a central longitudinal bore 15 which registers with the longitudinal bore 85 16 of the tubular shaft 10.

Removably attached to the outer end of the coiling head 14 is a thimble or eyelet 17 which is employed for guiding the wire 18 into the coiling head. In order to coil 90 the wire 18 as it passes through the head 14 to form a spiral, as best shown at 19 in Fig. 4, a pair of coiling pins 20 are extended transversely through the coiling head 14 and intersecting the bore 15 through the head, 95 said pins being preferably positioned to one side of the longitudinal axis of the bore and in spaced relation with each other.

Extending transversely through the coiling head 14 and at right angles to the coiling pins 20 is a recess 21 through which extends a bolt 22, the lower end of the bolt having a centrally disposed slot 23 for the reception of a roller 24. The roller is held normally stationary in the slot 23 by any 100 suitable means, as by introducing a screw 25 transversely through the bolt and centrally through the roller, one end of the screw having threads 26 for engagement with threads in the opening of the bolt 105 through which the screw extends, and an enlarged head 27 on the opposite end of the

screw which abuts against a shoulder 28 on the bolt 22. By constructing the screw in this manner, the roller 24 is securely clamped between the bifurcated ends of the bolt 22 and to insure that the roller will not rotate while in operation, one or both faces of the roller may be provided with ribs 29 which grip against or bite into the adjacent parts of the bolt.

- 10 The bolt 22 is adjusted longitudinally by threading the free end thereof and engaging a nut 30 therewith, said nut, when turned on to the bolt, pressing against one face of the coiling head 14, thus drawing the bolt longitudinally through the recess to the desired point. The bolt 22 is held against rotating in the recess 21 by making the diameter of the roller 24 greater than the diameter of the bolt so that the edge of the roller will 15 project beyond the slot 23 and by forming grooves 31 for the reception of the projecting edges of the roller, the bolt will be held against rotating movement.

It has been found by experience that in 20 order to produce the proper twisting or coiling results it is necessary to hold the roller against rotation so that the wire will merely slide over the roller, but as the passage of the wire over the roller gradually wears that 25 portion of the roller engaged by the wire, the face of the roller will eventually be so worn that the proper results cannot be accomplished, hence by attaching the roller to a bolt in the manner shown, the screw can 30 be loosened to permit the roller to rotate and by properly adjusting the roller to present a new section of the roller to the wire, the 35 entire peripheral surface of the roller can be successively used until the roller is entirely 40 worn out, thereby greatly enhancing the life of the roller.

In entering the wire 18 into the coiling head 14 the nut 30 is turned outwardly on the bolt 22 and the bolt moved longitudinally 45 through the recess until the end attached to the roller is positioned beyond the inner edges of the coiling pins so that the end of the wire will pass between the coiling pins and the roller. After the wire has been 50 properly positioned between the coiling pins and roller the nut 30 is again turned on to the bolt and the roller moved inwardly the required distance, said roller passing between the coiling pins. This causes the wire 55 to travel in a circuitous path and in view of the fact that the wire is fed in a straight line into the coiling head, while the coiling head rotates around the wire, a perfect spiral formation is produced.

60 The prime object in coiling the wire in this manner is to form an interlocking fence stay. As the wire is cut in prescribed lengths and then bent at its longitudinal center, it is absolutely necessary to have all 65 of the coils perfectly uniform as the bent

sections of the wire are interwound with each other and if there should be any variation in the coils, the stay could not be engaged with the strands of wire forming the fence and consequently the wire and labor 70 in coiling the same would be entirely lost. It is therefore necessary that the tubular shaft 10 of the coiling head 14 be positively driven so that there can be no slipping action between the driving shaft 2 and the 75 tubular shaft 10. This is accomplished, as previously stated, by employing a sprocket chain 8 and sprocket wheels 7 and 9, the proper tension being given to said chain by placing a sprocket idler 32 below the chain 80 8 between the sprockets 7 and 9, said idler being supported by a shaft 33 mounted in a bearing 34 on the frame 1.

It is likewise necessary that a positive feed be provided for feeding the wire into 85 the coiling head and one that will act in positive unison with the operation of the coiling head. To this end feed rolls 35 are mounted upon shafts 36, said rolls and shafts being arranged in pairs with one pair above 90 the other, said rolls having intermeshing gears 37, with the lower set of which meshes a gear 38 carried by an auxiliary shaft 39, said shaft being positively driven from the driving shaft 2 through the medium of intermeshing gears 40 and 41 and as the tubular shaft 10 is also positively driven from the driving shaft 2, said feeding roller and coiling head will be operated in perfect unison with each other. 95

It will be understood of course that instead of using a chain drive for the tubular shaft 10 a series of gears may be employed or any other suitable means for giving a positive drive to the tubular shaft or such 100 as will not permit any slippage between the driving shaft and tubular shaft.

As the wire travels through the coiling head it likewise passes through the bore 16 in the tubular shaft 10 and enters a trough 110 42 at the open end of the bore 16 and travels through said trough to any suitable cutting device for severing the wire into lengths.

The invention claimed is:

1. In a wire coiling mechanism the combination with a wire feeding device, of means to bend the wire into substantially spiral formation, comprising a rotatably mounted tubular section, a hollow head attached to one end of said tubular section, a thimble at the other end of said head, coiling pins extending transversely through the opening in said head and spaced apart, a roller mounted in said head between said coiling pins, means to clamp the faces of said roller to hold said roller against rotation, means to adjust said roller outward or between said coiling pins and means to positively rotate said tubular portion and head. 115
2. In a wire coiling mechanism the combination with a wire feeding device, of means to bend the wire into substantially spiral formation, comprising a rotatably mounted tubular section, a hollow head attached to one end of said tubular section, a thimble at the other end of said head, coiling pins extending transversely through the opening in said head and spaced apart, a roller mounted in said head between said coiling pins, means to clamp the faces of said roller to hold said roller against rotation, means to adjust said roller outward or between said coiling pins and means to positively rotate said tubular portion and head. 120
3. In a wire coiling mechanism the combination with a wire feeding device, of means to bend the wire into substantially spiral formation, comprising a rotatably mounted tubular section, a hollow head attached to one end of said tubular section, a thimble at the other end of said head, coiling pins extending transversely through the opening in said head and spaced apart, a roller mounted in said head between said coiling pins, means to clamp the faces of said roller to hold said roller against rotation, means to adjust said roller outward or between said coiling pins and means to positively rotate said tubular portion and head. 125
4. In a wire coiling mechanism the combination with a wire feeding device, of means to bend the wire into substantially spiral formation, comprising a rotatably mounted tubular section, a hollow head attached to one end of said tubular section, a thimble at the other end of said head, coiling pins extending transversely through the opening in said head and spaced apart, a roller mounted in said head between said coiling pins, means to clamp the faces of said roller to hold said roller against rotation, means to adjust said roller outward or between said coiling pins and means to positively rotate said tubular portion and head. 130

2. In a wire coiling mechanism, the combination with a wire feeding device and a supporting frame therefor, of a hollow shaft rotatably mounted on said frame, positive driving means for said hollow shaft, a head attached to one end of said hollow shaft, said head having a bore registering with the bore in said shaft, a guiding thimble attached to the free end of said head, a pair of coiling pins extending transversely through said head and intersecting the bore thereof at one side of the axis of the head, an adjusting bolt extending through said head between the coiling pins and at right angles thereto, a roller mounted in one end of said bolt, means to clamp the bolt against the faces of said roller to normally hold the roller against rotation and means to adjust said bolt longitudinally whereby the wire 15 will be caused to travel inwardly between said pins as the wire is fed into said head.

3. In a wire coiling device, a coiling head having a longitudinal bore and a transverse recess intersecting said bore, a pair of spaced coiling pins extending transversely through the coiling head, a bifurcated bolt extending through said recess, a roller between the bifurcated ends of the bolt, means to clamp the bifurcated ends of the bolt against 25 the faces of the roller to hold said roller against rotating movement, and means to

adjust said bolt longitudinally to move said roller to position between said coiling pins.

4. In a wire coiling mechanism, a rotatable coiling head having a longitudinally extending bore, and a transverse recess intersecting said bore, a coiling pin extending transversely through the bore at each side of the recess, a bolt extending through said recess, one end of the bolt being slotted, a roller positioned in the slot of the bolt, means to lock the parts of the bolt against said roller, means on the roller for engagement with the bolt for preventing rotation of the roller when in use, means co-operating with the roller for holding the bolt against rotation, and means to adjust said bolt longitudinally.

5. In a wire coiling mechanism, a coiling head having a central bore, and a laterally extending recess, a bolt adapted to enter said recess, one end of the bolt being slotted, a roller entering the slot in the end of the bolt, a screw extending through the bolt and roller for clamping said roller against rotation with respect to the bolt, and ribs on said roller adapted to bite into the adjacent part of the bolt to hold the roller in fixed relation with the bolt.

In witness whereof, I have hereunto affixed my signature.

CARL A. PORATH.
